INVENTOR

UNITED STATES PATENT OFFICE.

FRANCIS LEROY HORSPOOL, OF SALT LAKE CITY, UTAH, ASSIGNOR TO WILLIAM C. DILLON, OF FORT DODGE, IOWA.

BOLT LOCK FOR VAULT AND SAFE DOORS AND THE LIKE.

1,402,499.

Specification of Letters Patent.

Patented Jan. 3, 1922.

Application filed March 12, 1919. Serial No. 282,138.

To all whom it may concern:

Be it known that I, FRANCIS LEROY HORSPOOL, a citizen of the United States, residing at Salt Lake City, in the county of Salt Lake and State of Utah, have invented a new and useful Bolt Lock for Vault and Safe Doors and the like, of which the following is a specification.

My invention relates to improvements in emergency bolt locks, more especially to a bolt lock where a spring is used to throw the locking lug into its locked position when the combination lock which is on the vault door is broken off.

One object of my invention is to provide an emergency bolt lock, that will work by automatic action and lock all the bolts on the vault, or safe door when the spindle of the combination lock which is on the vault 20 or safe door has been driven in or broken off.

Another object of my invention is to provide an emergency bolt lock, that cannot be jarred loose and lock the vault or safe by the closing of the door.

Another object of my invention is to provide an emergency bolt lock, that is cheap in construction and can be applied to any style of vault or safe door by unskilled labor.

Another object of my invention is to provide an emergency bolt lock, that can be held firmly unlocked and locked automatically when the combination lock which is on the vault or safe door has been broken 35 into.

With these and other objects in view, my invention consists of the following novel construction and arrangement of parts, to be hereinafter described and claimed, reference 40 being had to the annexed drawings forming part of this specification and to the figures of reference marked thereon.

Figure 1 is an inside view of a vault door showing the invention attached.

Fig. 2 is a side view of Fig. 1, on the line $x-x$.

Fig. 3 is an enlarged section of the edge of the door, showing the locking lug in its unlocked position and ready for use.

Fig. 4 is an enlarged detail section of the inside of the door showing the invention as seen from the inside of the vault.

Fig. 5 is a detail side view of the trigger bracket.

Fig. 6 is a detail side view of the locking lug.

C designates an ordinary vault door, D the combination lock casing, E the horizontal locking bolts of the door, F the tie plate for the locking bolts E, G the angle iron 60 on the inside of the door for supporting the horizontal locking bolts E, H the door frame, 1 the threaded bolt, 2 the spring, 3 and 3' the tension nuts, for holding the spring 2 in tension, 2' and 2'' the nuts for 65 securing the bolt 1 to the angle iron G, 4 the locking lug, 5 a bracket mounted on the bolt 1 for supporting the trigger 7, 6 and 6' the nuts for holding the bracket 5 firmly 70 in place, 7 the trigger for holding the locking lug 4 in its unlocked position, 8 the wire extending to the combination lock casing D, 9 the wire that is attached to the stem 32 of the handle 33; the wire 9 is only used when the handle 33 is of old style make 75 and is secured thereto by the nut on said handle (not shown); 10 is the rivet for securing the trigger to the bracket 5.

Having thus described the parts of my invention, I will now endeavor to illustrate 80 the operation and assembling of same.

I start by taking the bolt 1 and screw on the nuts 3, 3' and 2''. Now I place onto the bolt 1 the spring 2 and place the end 12 of said spring into the hole 11 of the nut 3. 85 Now I place onto the bolt 1 the locking lug 4 and place the end 14 of the spring 2 into the hole 13 in the locking lug 4. Now I place on the nut 6. Now the bracket 5 and the nut 6'. Now I take the trigger 7 and 90 place it into the notch 30 of the bracket 5 and pivot it thereto by means of the rivet 10. Now I attach the wire 8 to the trigger 7 at 15, also attach the wire 9 when necessary. The invention is now ready to be 95 applied to the vault door.

In applying my invention to a vault door, I first drill a hole 17 into the angle iron G at any desired place. Now I place the end 16 of the bolt 1 into the hole 17. Now I 100 place onto the end 16 the nut 2' then tighten up the nut 2'' against the angle iron G. Now I adjust the locking lug 4 so it will just clear the back of the tie plate F when the bolts E are in their locked position by 105 turning the nuts 6 and 6'. To increase the tension of the spring 2 I turn the nut 3 on the bolt 1 till the required tension has been

secured. To prevent the nut 3 from turning, I tighten the nut 3' against the nut 3. Now I take the wire 8 and secure it over the back of the combination lock casing D and the back of the combination lock 19 then I secure the end 20 to the door by means of a screw, which is screwed into the door. In the event that the wire 9 is to be used I attach one end to the hole 15 in the trigger 7 and the other end to the inner end 32 of the handle 33. To set the locking lug 4 into its unlocked position so it will be ready for use, I place it into a vertical position and place the trigger 7 back of the locking lug 4 as shown. The locking lug 4 is held firmly against the trigger 7 by the tension of the spring 2.

In the event that the combination mechanism is tampered with in any way by unauthorized persons, such as burglars, who undertake to enter the vault by breaking through the combination lock and driving in the spindle which pushes off the back of the combination lock 19, thus causing a pull on the wire 8 which in turn lifts the trigger 7 into the position as shown by dotted lines 23 Fig. 4, thus releasing the locking lug 4 and allowing it to be thrown into the position as shown by dotted lines 24 Fig. 3. In the event that the wire 9 is to be used it will operate the trigger 7 in the same manner as the wire 8 by driving in the stem 32 of the handle 33.

After the safe door has been closed and the locking lug 4 has been thrown into its locking position and I wish to open the door, I drill a hole into the face of the door just above the locking lug 4 and then insert a wire loop into the hole and loop it over the end 22 of the locking lug 4 and then pull the locking lug 4 back into its unlocked position as shown in Fig. 3, and then turn the handle 33 and the door will come open.

The location of the hole to be drilled into the face of the door, is taken by measurement by the party who places the bolt onto the door.

The above principles are also applied to a safe when the bolt is to be applied.

Having thus described my invention, what I claim as new and desire to secure by Letters Patent, is:

1. A device of the character described comprising a bolt having a thread cut thereon, nuts on said bolt, a locking lug on said bolt, a spring surrounding said bolt for throwing said locking lug into a locked position, a bracket on said bolt for supporting a trigger, a trigger carried by said bracket for holding said locking lug in an unlocked position, a wire attached to said trigger and over the back of the combination lock casing and secured to the door by means of a screw, another wire attached to said

trigger and to the inner end of the handle of 65 the door, substantially as and for the purpose set forth.

2. A device of the character described comprising a bolt having a thread cut thereon, nuts screwed on said bolt, a spring 70 surrounding said bolt, a locking lug on said bolt, said locking lug and one of said nuts being provided with a hole for receiving the ends of said spring, a trigger for holding said locking lug in an unlocked position, 75 a bracket mounted on said bolt for supporting said trigger, a pin for securing said trigger to said bracket and nuts for holding said bracket in the proper position.

3. A device of the character described comprising a bolt having a thread cut thereon, nuts screwed onto said thread, a locking lug on said bolt, nuts on said bolt for holding said locking lug in the desired position, 85 a spring surrounding said bolt for operating said locking lug, nuts for holding said spring in the desired tension on said bolt, a trigger for holding said locking lug in unlocked position, a bracket secured on 90 said bolt for supporting said trigger, substantially as and for the purpose set forth.

4. The combination with a vault door, of a locking device for the door including a bolt mechanism and a combination mechanism, of 95 a rod carried by and arranged in parallel relation with the door, a block rotatably mounted on the rod and arranged at right angles to the bolt mechanism, means for preventing the accidental rotation of the block, 100 and means for rotating the block upon the destroying of the combination mechanism.

5. The combination with a vault door having a flange extending adjacent to the forward edge thereof, of a locking device for 105 the door including a plurality of spaced bolts arranged to be projected through the flange, and a bar connecting the bolts, a rod secured to the door flange and extending in parallel relation to the door, a block rotatably mounted on the rod and arranged at right angles to the bar and having a flat face arranged to normally lie in parallel relation to the bar to permit movement thereof, and a connector secured to the block and having its lower end 110 anchored adjacent to the combination mechanism.

6. The combination with a vault door, of a locking device for the door including a bolt mechanism and combination mechanism, a 120 rod carried by the door, a block arranged at right angles to the bolt mechanism and adapted to be moved into and out of engagement with the bolt mechanism, spring means carried by the rod for normally urging the 125 block into the path of the bolt mechanism, and frangible means operatively connected to said block and extended across the combi-

nation mechanism for normally holding the block out of the path of the bolt mechanism against the tension of said spring means.

7. The combination with a vault door, of
5 a bolt mechanism and combination mechanism, a rod carried by and arranged in parallel relation to the door, a block rotatably mounted on the rod and arranged at right angles to the bolt mechanism and adapted
10 to be moved into and out of the path of the bolt mechanism, a spring carried by the rod and operatively connected to said block to move the same into the path of the bolt mechanism, and a cable operatively connected to said block and extending across the combination mechanism for normally holding the block out of the path of the bolt mechanism against the tension of said spring.

8. The combination with a door having a
20 locking mechanism, and a combination lock-

ing device, of an auxiliary locking device comprising a rod, a locking block rotatably mounted on said rod adapted in one position to co-act with the locking mechanism, of the door for holding it in locked position, a 25 yielding device for holding said block in said position, and means operatively connected with said block and extended to position adjacent to said combination lock device for holding the block in an inoperative position 30 against the action of said yielding device, whereby upon the movement of the combination lock device from normal position or the destruction of said means, said yielding device will move the locking block to said first 35 mentioned position.
